[57] CLAIM

The ornamental design for a tape cutter, as shown and described.

DESCRIPTION

FIG. 1 is a front elevational view of a tape cutter showing my new design;

FIG. 2 is a rear elevational view;

FIG. 3 is a top plan view;

FIG. 4 is a bottom plan view; and

FIG. 5 is a right side elevational view, the left side being a mirror image thereof.

*FIG. 1**FIG. 2**FIG. 3**FIG. 4**FIG. 5*
